UNITED STATES PATENT OFFICE.

BRUNO WESSELMANN, OF HAMBURG, ASSIGNOR OF ONE-HALF TO WILHELM LUCHT, OF ALTONA, GERMANY.

PENCIL-SHARPENER.

SPECIFICATION forming part of Letters Patent No. 423,845, dated March 18, 1890.

Application filed December 27, 1889. Serial No. 335,147. (No model.) Patented in Germany February 21, 1889, No. 48,647.

To all whom it may concern:

Be it known that I, BRUNO WESSELMANN, a citizen of the German Empire, residing at Hamburg, in the German Empire, have invented new and useful Improvements in Pencil-Sharpener, (for which I have obtained a patent in Germany, No. 48,647, dated February 21, 1889,) of which the following is a specification.

10 This invention has for its object to provide a novel, efficient, and desirable pencil-sharpener, which can be economically manufactured in large quantities by simple means; and to such end the invention consists in the 15 features of construction and the combination or arrangement of devices hereinafter described and claimed, reference being made to the accompanying drawings, in which—

Figure 1 is a plan view of a pencil-sharpener. 20 Fig. 2 is a section along A B, Fig. 1. Fig. 2^a is a detail view of a cutter. Fig. 3 is a section along C D, Fig. 1. Fig. 4 is a plan view of a modification of Fig. 1. Fig. 5 is a section along E F, Fig. 4. Fig. 6 is a section 25 along G H, Fig. 4. Fig. 7 is a plan view of a pencil-sharpener with a cigar-tip cutter. Fig. 8 is a side elevation of Fig. 7. Fig. 9 is a plan view of a pencil-sharpener with an eraser-holder. Fig. 10 is a side elevation of Fig. 9.

30 The sharpener is shown consisting of two plates or sections *a b*, each struck up with a semicircular projection to form a receiving-space *h* for the pencil, said plates being secured together in any suitable way, such as 35 by bending of the edges.

In a suitable recess between the plates is arranged the knife or cutter *m*, the edge of which projects obliquely into the receiving-space *h*, whereby a pencil introduced into 40 said space can be conically sharpened. The knife shown in Figs. 1 to 3 consists of a single suitably-bent steel plate, Fig. 2^a, and said knife is secured in place partly by fitting into the space between the plates and partly by 45 having an opening *o* in one of its branches, into which opening fits a suitable shoulder or projection on one of the plates or sections.

In Figs. 4 to 6 the sharpener is shown with an adjustable cutter, so as to enable the pen-

cil to be sharpened with more or less taper. 50 The set-screw *s*, guided by the guide or nut *k*, enables the cutter to be adjusted to vary the taper produced by the cutter on the pencil. The cutter in this case consists of a massive piece of material and can turn either about 55 a lug or elevation on a plate or section or about a bolt passed through the plates. The bolt is used if the knife is to be made removable, in which case the edges of the plates back of the knife are open or separate, so 60 that the knife can be removed or introduced through the opening. The spring *i* continually presses the knife against the set-screw *s*.

The pencil-sharpener, Figs. 4 to 6, is also combined with a device for cutting off cigar-tips. The cigar-tip cutter *c* is movably applied between the plates *a b*. Said plates are not united at this part along their edges and have play-room for the tip-cutter *c* and the spring *f*, bent about the four-cornered pivot or shank *t*. The spring presses the tip-cutter *c* continually to its closed position. The shank *t* is held at its edges in four-cornered holes or depressions in the plates. If a cigar-tip is to be cut off, the tip-cutter by means of its projecting handle is first opened. Then the tip of the cigar is inserted into the hole *u*, and the tip-cutter then being closed the cigar-tip will 75 be cut off.

The pencil-sharpener in Figs. 7 and 8 has 80 a lengthened form, and the plates *a b* are not united along the edges, but by means of the rivets *v*. The set-screw *s* for the knife *m*, in the case of Figs. 7 and 8, also serves to hold the plates *a b* together. A rivet *v'* serves as a 85 pivot for the cigar-tip cutter *c*. The receiving-space *h* in said Figs. 7 and 8 is shown as being only formed in the under plate in the shape of a projecting cone.

In the construction shown in Figs. 9 and 10 90 only one plate is employed—namely, the plate *a*, provided with the space *h*. On said plate the cigar-tip cutter *c* is secured by the screw or pivot *t*. The knife *m* in this case sits about the set-screw *s*, said set-screw passing 95 through a slot, so that said screw, with the knife, can be adjusted relatively to the space *h*.

In addition to the cigar-tip cutter, the pencil-sharpener has a holder *q* for a rubber or eraser, said holder *q* consisting of a hollow or recessed attachment into which the eraser of 5 suitable form can be fitted and secured.

What I claim as new, and desire to secure by Letters Patent, is—

1. A pencil-sharpener consisting of a flat plate struck up with a semicircular projection to form the pencil-receiving groove *h*, and a cutter *m*, formed separate from and attached to one side of the grooved plate in the plane parallel thereto and having an oblique cutting-edge extending diagonally into the 15 pencil-receiving groove, substantially as described.

2. A pencil-sharpener consisting of two flat plates united together and each struck up with a semicircular projection to form between the plates a circular pencil-receiving space *h*, and a flat cutter *m*, arranged between and parallel to the two plates and having an oblique cutting-edge extending diagonally into the circular pencil-receiving space between the plates, substantially as described. 20

3. A pencil-sharpener consisting of two flat plates united together and each struck up with a semicircular projection to form between the plates a circular pencil-receiving space *h*, a cutter *m*, pivoted between the two plates and having its cutting-edge extending obliquely into the pencil-receiving space, a 25 screw-nut, and a screw engaging the nut between the plates for adjusting the cutter

more or less into the pencil-receiving space, 35 substantially as described.

4. A pencil-sharpener consisting of two plates united together and provided with a pencil-receiving space, a cutter movably arranged between the plates and having its cutting-edge extended obliquely across the pencil-receiving space, and a screw for adjusting the cutter more or less into the said space, 40 substantially as described.

5. A pencil-sharpener consisting of a flat plate struck up with a semicircular projection to form a pencil-receiving space, a flat cutter mounted on the plate with its cutting-edge extending obliquely into the pencil-receiving space, and a cigar-tip-cutter blade 45 supported by the plate and moving in a plane parallel to the latter, substantially as described.

6. A pencil-sharpener comprising a plate having a cigar-tip-receiving orifice *u*, a pencil-receiving space *h*, and a cutter *m*, and having a swinging cigar-tip-cutter blade moving in a plane parallel with the plate to cut a cigar-tip inserted through the orifice therein, 50 substantially as described.

In testimony whereof I have hereunto set my hand in the presence of two subscribing witnesses.

BRUNO WESSELMANN.
